ADSORPTION REFRIGERATION SYSTEM

Alwin B. Newton, Minneapolis, Minn., assignor to
Minneapolis-Honeywell Regulator Company,
Minneapolis, Minn., a corporation of Delaware

Application April 17, 1939, Serial No. 268,233

14 Claims. (Cl. 62—5)

This invention relates to a refrigeration system and more particularly to a control system for that type of refrigeration system known as an adsorption refrigeration system.

One of the objects of this invention is the provision of a control means for activating the adsorber of an adsorption refrigeration system.

More particularly it is an object of this invention to provide, in an adsorption refrigeration system, a heating means for activating the adsorber, means for placing the heating means in operation whenever the adsorber temperature is sufficiently low and the evaporator temperature is sufficiently high and for terminating operation of the heating means when the adsorber temperature drops to a predetermined value.

A further object of this invention is to provide, in an adsorption refrigeration system means for alternately adding heat to the adsorber for activating purposes, and reducing the temperature of the adsorber to reduce the pressure therein, initiating operation of the heating means whenever the adsorber temperature and the evaporator temperature are sufficiently low, terminating operation of the heating means whenever the adsorber temperature rises to a predetermined value, and rendering the cooling means effective whenever the heating means is rendered inoperative.

Other objects and advantages of this invention will become apparent upon a study of the specification, claims, and appended drawings wherein like reference characters represent like parts in the various views and wherein

Figure 1 is a schematic showing of an adsorption refrigeration system embodying the control features of my invention.

Figure 2 is a view with certain parts in cross section of the valve for controlling the flow of fuel to the heating means, and the actuating means therefor.

Figure 3 is a view in cross section of the valve for controlling the cooling means for the adsorber, and

Figure 4 is a modification of the control system of Figure 1 applied to a refrigeration system of the same type as shown in Figure 1.

Referring more particularly to Figure 1 the reference character 10 represents an evaporator which receives refrigerant from the receiver 11 connected to the condenser 12 which is in turn connected to the adsorber 13. The adsorber 13 may be provided with any suitable adsorbing material such as activated carbon illustrated by the reference character 14. The outlet of the

evaporator 10 communicates by means of the pipe 15 with the adsorber 13 and upon heating of the adsorber in order to activate the same, refrigerant flows into the evaporator 10 by way of the condenser 12, receiver 11 and pipe 16. Reverse flow of the refrigerant is prevented by the check valves 18 and 19.

Located within the adsorber 13 is a heating coil 20 connected to the receptacle 21 which is to be heated, the coil 20 and receptacle 21 containing a suitable heat exchange medium which may be in the form of a volatile fluid and for this purpose a suitable refrigerating medium such as Carrene may be utilized. Upon applying heat to the receptacle 21 the Carrene is vaporized and flows upwardly through pipes 22 and 23 into the coil 20 in the adsorber 13, the fluid returning to the receptacle 21 by way of the pipe 24 provided with a trap 25. It will be apparent that as the fluid in the receptacle 21 is heated and circulates through the coil 20 in the adsorber, the temperature of the adsorber will be increased and the refrigerant which has been adsorbed by the activated carbon therein will be driven off and flow into the evaporator 10 by way of the condenser 12.

Communicating with the receptacle 21 by way of the pipe 22 and the pipe 28 is a coil 30 which forms a cooling or heat dissipating coil and 30 which may be placed in any suitable location whereby it will be cooled by the surrounding medium. The outlet of this coil is connected to a valve 31, the outlet of this valve communicating by means of the pipe 32 with the pipe 23.

The valve 31 is shown in detail in Figure 3 and is seen to comprise an inlet opening 34 controlled by a valve element 35 which is normally biased to open position by means of the spring 36, a bellows 37 being operatively connected to the valve element and being arranged to close the valve upon expansion of the bellows. The bellows is connected by means of a capillary tube 40 to a bulb 41 which is shown to be disposed over the burner 42 which is provided for heating the receptacle 21, this tube, bulb, and bellows being provided with a fill such as a suitable volatile fill. When the burner 42 is in operation the bulb 41 will be heated up and the volatile fill therein will cause expansion of the bellows 37 which in turn causes the valve element 35 to close off the inlet port 34 so that any fluid which is in the coil 30 is not permitted to escape therefrom by way of this valve.

The burner 42 is supplied with a combustible fluid by way of a pipe 43 controlled by a valve

44, there being a suitable pilot burner 45 connected to the inlet side of the valve 44 for igniting the fuel issuing from the burner 42 when the valve 44 is opened. When the burner 42 is in operation the valve 31 controlling the heat dissipating coil 30 will be closed as described above. The fluid within the receptacle 21 will be vaporized and will pass by way of the pipes 22 and 23 into the heating coil 20 and will return by way of the pipe 24 to the receptacle 21. At the same time the fluid being vaporized in the receptacle 21 will flow by way of the pipes 22 and 28 into the heat dissipating coil 30 but will be prevented from leaving the coil since the valve 31 is at this time closed. The fluid will accordingly be trapped within the coil 30 and will condense therein. The refrigerant which has been adsorbed by the material within the adsorber 13 will be driven into the evaporator 10 by way of the condenser 12. After a certain length of time, substantially all of the refrigerant will have been driven out of the adsorber and the burner 42 will then be shut off by means to be hereinafter set forth. When the burner shuts off the bulb 41 will cool down thus causing a reduction in pressure in the bellows 37 of the valve 31 so that this valve will now open. The fluid which has condensed in the coil 30 will now flow by way of the valve 31, pipes 32, 23 into the coil 20 in the adsorber 13. The fluid in the coil 30 will be relatively cool compared to the temperature of the adsorber so that this flow of the fluid from the coil 30 through the cooling coil 20 of the adsorber will reduce the temperature in the adsorber and consequently reduce the pressure therein. As the pressure within the adsorber decreases the refrigerant in the evaporator will vaporize and flow back to the adsorber and the temperature of the evaporator 10 will consequently decrease. The evaporator 10 therefore effects refrigeration and the cooling effect of the evaporator will continue until all of the refrigerant therein has been drawn back into the adsorber 13. When this happens the temperature of the evaporator will again start to rise above the minimum value attained thereby and an activating cycle of the type described above will be resumed by means to be described.

Referring more particularly to Figure 2, the details of the valve 44 and operating mechanism therefor is illustrated. This valve is shown to include an inlet 58, an outlet 51, and a valve element 52 for controlling flow from the inlet to the outlet thereof. The valve element 52 is sealed from the operating chamber 53 by means of the diaphragm 54 and the valve element is biased to open position by means of the spring 55. A housing 60 is located on top of the valve body and in the upper wall of this housing are suitably mounted operating bellows 61, 62, and 63. The operating bellows 61 controls the position of a lever 65 pivoted at 66 and biased upwardly by the tension spring 67 having a suitable adjusting means 68 for adjusting the tension thereof. The end of the lever 65 remote from the pivot 66 is connected by means of a spring 70 to a lever 71 pivoted at 72, the spring 70 and lever 65 forming a snap acting mechanism for the lever 71. Upward movement of the lever 71 is limited by means of a suitable stop 72 and the extremity of the lever 71 overlies the top of the valve element 52.

The bellows 62 controls the position of a lever 75 pivoted at 76 and biased upwardly by the

10 tension spring 77 having the adjusting means 78. The bellows 63 controls the position of a lever 80 pivoted at 81 and having its right end biased upwardly by the tension spring 82 having means 83 for adjusting the tension thereof. The adjacent ends of the levers 75 and 80 control the position of the lever 85 pivoted at 86 and having a portion 87 bearing against the upper side of the valve element 52.

15 Expansion of the bellows 61 causes downward movement of the lever 65 against the force of the tension spring 67 and after this lever has been moved downwardly a sufficient amount, the spring 70 on passing the dead center position will cause the lever 71 to move downwardly with a snap action which will force the valve element 52 to its closed position against the force of the spring 55. As the bellows 61 collapses and the lever 65 moves upwardly it will engage the member 90 located at the lower extremity of the compression spring 91 provided with a suitable adjusting means 92 so that this spring will oppose upward movement of the lever 65 after it has moved upwardly a short distance above the position illustrated. In order for the lever 65 to snap the lever 71 back to the position illustrated, the lever 64 must move upwardly beyond the position illustrated in order to move the spring 70 back through the dead center position so that the pressure within the bellows 61 must be considerably less in order to cause the lever 71 to move back to the position illustrated than existed therein when the lever 71 was snapped downwardly since the spring 91 opposes the action of the spring 67. The amount that the pressure must be reduced in the bellows 61 will depend upon the adjustment of the spring 91 and accordingly this spring forms a differential adjustment for the lever 71. Suitable stops 95 are provided for limiting downward movement of the member 90 so that after the lever 65 has moved to the position illustrated the spring 91 has no effect thereon. It will be understood that these stops will be out of the path of movement of the lever 65. It will accordingly be seen that the valve 52 will be closed whenever the pressure within the bellows 61 rises to a sufficiently high value and the valve cannot be reopened until the pressure within the bellows has dropped to a value substantially less than the closing pressure thereon.

50 As the bellows 62 expands and lever 75 is moved downwardly against the force of spring 77 the lever 85 will be moved downwardly, thus moving the valve towards closed position, but this lever is not operated with a snap action as is the lever 71. The spring 82 associated with the lever 80 biases this lever in a direction to move the lever 85 downwardly and the action of this spring is opposed by an increase in pressure in the bellows 63.

55 It will be apparent therefore that the lever 85 will move downwardly as the bellows 62 expands or as the bellows 63 collapses under the influence of the spring 82 thus moving the valve toward closed position, or if the valve is closed by the lever 71, these bellows may prevent reopening thereof.

60 The interior of the bellows 61 is connected by means of the capillary tube 100 to a bulb 101 which is shown to be located against the outer surface of the adsorber 13 but which if desired may be located within the adsorber to sense the temperature thereof. This bulb, tube, and bellows is provided with a suitable fill and upon an

increase in temperature of the adsorber the bellows 61 will expand and when the temperature of the adsorber rises to a sufficiently high value, such as 225° F. the bellows 61 will have expanded sufficiently to move the lever 71 down with a snap action, thus moving the valve element 52 to closed position. When the temperature of the adsorber drops to a relatively low value such as 150° F. the bellows 61 will have collapsed sufficiently to cause movement of the lever 71 back to its original position so that if the valve element 52 is not held closed by any other means, it will be opened again when the temperature of the adsorber drops sufficiently.

The interior of the bellows 62 is connected by means of the tube 105 with the interior of the receptacle 21 so that if the pressure within this receptacle rises sufficiently such as to a value of 160 lbs. sq. inch, the bellows 62 will expand causing downward movement of the lever 85 through the lever 75 and consequent moving of the valve element towards closed position, thus reducing or cutting off the supply of fuel to the burner 42 so that the pressure within the receptacle 21 will not increase to a dangerous value.

The interior of the bellows 63 is connected by means of the capillary tube 106 to the bulb 107 which may be located in contact with the evaporator 10 to sense the temperature thereof, the tube, bulb and bellows having a suitable fill so that the bellows 63 will expand or contract in response to increases or decreases in the temperature of the evaporator 10. Whenever the temperature of the evaporator is above a certain value as 28° F. the bellows 63 will be sufficiently expanded so that the lever 80 does not exert any closing force on the valve 52 through the lever 85 but as the temperature of the evaporator drops below this value and the bellows 63 contracts, the spring 82 will be effective to move the inner end of the lever 80 downwardly thus causing the valve 52 to move towards closed position.

Assume now that the heater 42 is in operation for activating the adsorber at which time the valve and operating means therefor are in the positions illustrated. The temperature of the adsorber will gradually increase and after the temperature has risen to a value such as 225° F. which is an indication that substantially all of the adsorbed refrigerant has been driven out of the adsorber, the expansion of the bellows 61 will move the valve 52 to closed position with a snap action. The temperature of the evaporator will now start to decrease as explained heretofore and the temperature will decrease rather rapidly causing a collapse of the bellows 63 so that the lever 80 under the influence of the spring 82 will hold the lever 85 downwardly in valve closing position. This action will take place rather rapidly and before the temperature of the adsorber has decreased to the value at which lever 71 is moved back to the position illustrated. The valve is thus at this time held closed both by reason of the low evaporator temperature and the high adsorber temperature. As the temperature of the adsorber decreases to a relatively low value as 150° the lever 71 will snap upwardly but if the evaporator temperature is still sufficiently low the valve 52 will be held closed by the spring 82 acting on the lever 80. As the evaporator 10 becomes emptied of refrigerant which has been adsorbed by the adsorber 13 the temperature thereof will start to rise rapidly and after it has risen to a sufficiently high value such as 26° F. the bellows 63 will have expanded suf-

ficiently to overcome the tension of the spring 82 and if the adsorber temperature is sufficiently low at this time as it will be in the normal operation of the system, the valve 52 will be reopened thus initiating a new activating cycle of the system. The valve 31 will now close under the influence of heat from the burner 42 thus trapping a new charge of fluid in the condenser 30 as heretofore described. If at any time during the activating cycle the pressure within the receptacle 21 becomes excessive the bellows 62 will be expanded and will overcome the tension of the spring 77 to move the valve 52 to its closed position. This excessive pressure will not normally be attained during the operation of the system but this operating bellows 62 is provided as a safety measure.

It will thus be seen that with the system described in Figure 1 the valve 44 controlling the supply of fuel to the burner 42 is controlled directly by the three pressure devices 61, 62, and 63 which respond to the adsorber temperature, the pressure in the receptacle 21 and evaporator temperature, respectively, in a manner to automatically and effectively control the activating and cooling cycles of the refrigeration system, in conjunction with the valve 31 controlling the condenser or heat dissipating coil 30.

Referring now to Figure 4, an electrically controlled valve 110 is provided for controlling the flow of fuel to the burner 42. A motor 111 is provided for controlling the operation of this valve and this motor may be of any suitable construction such as a solenoid which when energized causes opening of the valve 110 and when deenergized permits the valve to close under the influence of gravity or any suitable biasing means (not shown).

For controlling the solenoid 111 mercury switches 115, 116, and 117 are provided. The position of the switch 115 is controlled by the bellows 120 which responds to the pressure within the receptacle 21 and when this pressure rises sufficiently the bellows 120 moves the switch 115 to circuit breaking position against the tension of the spring 121.

The switch 116 is controlled by a bellows 122 connected by means of the capillary tube 123 with the bulb 124 positioned to respond to the temperature of the adsorber 13, the tube, bulb and bellows being provided with a suitable fill so that when the temperature of the adsorber rises sufficiently the expansion of the bellows 122 will move the switch 116 to the circuit breaking position. This switch is a wide differential switch and may be curved longitudinally as illustrated so that the mercury element in the switch will be moved to the circuit making position when the temperature of the adsorber drops to a value such as 150° F. and will not move to circuit breaking position until the temperature of the adsorber has risen to some high value such as 225° F. It will be understood of course that any other suitable arrangement may be utilized for obtaining a wide operating differential of the switch 116 such for example as means of the type shown in Figure 2 for obtaining a wide adjustable operating differential of the lever 71.

The position of the switch 117 is controlled by the bellows 130 connected by the capillary tube 131 to the bulb 132 positioned to respond to the temperature of the evaporator 10. This switch moves to open position upon a sufficient decrease in evaporator temperature and moves to the circuit making position when the evap-

orator temperature rises to some value such as 28° F.

With the switches 115, 116, and 117 in the positions illustrated, power is supplied to the valve motor or solenoid 111 by way of conductor 140, switch 117, conductor 141, switch 116, conductor 142, switch 115, conductor 143, solenoid 111 and conductor 144, the conductors 140 and 144 being connected to a suitable source of power (not shown). Accordingly with the switches in the positions illustrated, the adsorber temperature is low and the evaporator temperature is high, valve 110 is open and burner 42 is in operation and accordingly an activating cycle is going on. During this activating cycle it will be apparent that the evaporator temperature will not be decreasing to open the switch 117 so this switch will remain closed during the activating cycle. Should the pressure within receptacle 21 become excessive which will happen only under abnormal conditions, the switch 115 will open, deenergizing solenoid 111 and interrupting the activating cycle. Normally however the activating cycle will continue until the temperature of the adsorber rises to a high value such as 225° F. whereupon switch 116 will be moved to open position thus deenergizing solenoid 111 and closing valve 110. When the valve 110 closes, a refrigerating cycle will commence as explained in connection with Figure 1 and at this time the evaporator temperature will rapidly decrease and the switch 117 will move to open position before the adsorber temperature drops sufficiently to cause closure of the switch 116. Accordingly the refrigerating or cooling cycle will continue until both the adsorber temperature decreases to a predetermined value such as 150° F. and the evaporator temperature rises to a high value such as 28° F. which will happen very soon after the evaporator 10 has been emptied of its refrigerant. Accordingly the system shown in this figure accomplishes electrically exactly what is accomplished by the direct acting pressure devices of Figure 1.

In the outlet of the evaporator 10 is provided a valve 150 biased by means of a spring 151 towards closed position. A bellows 152 exerts an opening force on the valve 150 when the temperature of the evaporator rises, this bellows being connected by the capillary tube 153 to the bulb 154 located in contact with the evaporator to sense the temperature thereof. The valve 150 accordingly operates to control the flow of refrigerant from the evaporator in a manner to maintain a substantially constant evaporator temperature during the cooling period thereof. It should be understood that this valve may also be applied to the system of Figure 1 or if desired this valve may be eliminated from the system shown in Figure 4. Moreover, the bulb 154 may respond to box temperature instead of evaporator temperature if desired to maintain a constant box temperature.

It will thus be seen that I have provided a completely automatic control system for use with an adsorption type refrigeration system for controlling the activating and cooling cycles thereof either electrically or by direct acting pressure responsive mechanism and it will be understood that any equivalent type of control arrangement may be utilized without departing from the spirit and scope of the present invention. Also many modifications of the details illustrated herein may become apparent to those skilled in the art and it should therefore be understood that this

invention is to be limited only by the scope of the appended claims.

I claim as my invention:

1. In an adsorption refrigeration system of the class described, an adsorber, a condenser and an evaporator operatively connected together, heating means for activating the adsorber, means responsive to the temperature of the adsorber and the temperature of the evaporator for initiating operation of the heating means and responsive to the temperature of the adsorber for terminating operation of the heating means, and means responsive to the temperature of the evaporator for controlling the flow of refrigerant therethrough.
2. In an adsorption refrigeration system of the class described, an adsorber, a condenser and an evaporator operatively connected together, means for heating the adsorber, means for cooling the adsorber, means responsive to the temperature of the adsorber and the temperature of the evaporator for initiating operation of the heating means and responsive to the temperature of the adsorber for terminating operation of the heating means, means responsive to operation of the heating means for interrupting operation of the cooling means, and means responsive to the temperature of the evaporator for controlling the flow of refrigerant through the evaporator.
3. In an adsorption refrigeration system of the class described, an adsorber, a condenser and an evaporator operatively connected together, heat exchanger means associated with said adsorber for adding heat thereto or extracting heat therefrom, said heat exchanger means including a heat exchanger coil associated with said adsorber, heating means for supplying heat to a medium circulating through said heat exchanger coil, cooling means for cooling said adsorber, control means for controlling the operation of the heating means, said control means including means for initiating operation of the heating means in response to a low adsorber temperature and a high evaporator temperature and for terminating operation of the heating means in response to a high adsorber temperature, and means responsive to operation of the heating means for rendering said cooling means ineffective.
4. In an adsorption refrigeration system of the kind described, an adsorber, a condenser and an evaporator operatively connected together, means for activating the adsorber and for causing a reduction of a pressure therein, said means including a fluid fuel burner, valve means for controlling the flow of fuel to said burner, a plurality of pressure responsive means acting directly on said valve means to control the position thereof, means rendering one of said pressure responsive means responsive to a pressure corresponding to the temperature of the adsorber, means rendering a second of said pressure responsive means responsive to the temperature of the evaporator, means causing said one pressure responsive means to close the valve means when the adsorber temperature attains a predetermined high value and preventing opening of the valve means until the adsorber temperature drops to a value substantially lower than the value at which the valve means was closed, and means causing the second of said pressure responsive means to maintain the valve means in its closed position until the temperature of the evaporator has risen to a predetermined value.

5. In an adsorption refrigeration system of the kind described, an adsorber, a condenser and an evaporator operatively connected together, heating means for activating the adsorber, said heating means including a heating coil within the adsorber through which flows a heat exchange medium and a fluid fuel burner for heating said medium exteriorly of said adsorber, a plurality of pressure responsive means acting directly on said valve means to control the position thereof, means rendering one of said pressure responsive means responsive to the temperature of the adsorber, means rendering a second of said pressure responsive means responsive to the temperature of the evaporator, means rendering a third of said pressure responsive means responsive to the pressure of said heat exchange medium, means causing said one pressure responsive means to close the valve means when the adsorber temperature attains a predetermined high value and preventing opening of the valve means until the adsorber temperature drops to a value substantially lower than the value at which the valve means was closed, means causing the second of said pressure responsive means to maintain the valve means in its closed position until the temperature of the evaporator has risen to a predetermined value, and means causing said third pressure responsive means to move the valve means towards closed position as the pressure of the heat exchange medium becomes excessive.

6. In an adsorption refrigeration system of the kind described, an adsorber, a condenser and an evaporator operatively connected together, heating means for activating the adsorber, electrically operated means for causing operation of the heating means in response to the energization thereof, a control circuit for said electrical operated means including a first switch means responsive to the temperature of the adsorber, said switching means having a relatively wide differential and a second switch means responsive to the temperature of the evaporator, said first switch means being arranged to close in response to a low adsorber temperature, said second switch means being arranged to close when the temperature of the evaporator rises above a predetermined value, and said first switch means being arranged to open in response to a relatively high adsorber temperature.

7. In an adsorption refrigeration system of the kind described, an adsorber, a condenser and an evaporator operatively connected together, heating means for activating the adsorber, electrically operated means for causing operation of the heating means in response to the energization thereof, a control circuit for said electrically operated means including a first wide differential switch means responsive to the temperature of the adsorber and a second narrow differential switch means responsive to the temperature of the evaporator, said first switch means being arranged to close in response to a low adsorber temperature and said second switch means being arranged to close when the temperature of the evaporator rises above a predetermined value, and means responsive to the temperature of said evaporator for controlling the flow of refrigerant therefrom.

8. In an adsorption refrigeration system of the class described, an adsorber, a condenser and an evaporator operatively connected together, a heat exchanger system including a heat exchanger

coil within said adsorber containing a heat exchange medium in the form of a volatile fluid, means for heating the heat exchange medium passing through said coil, a heat dissipating coil located externally of said adsorber and in communication with said heat exchanger coil, control means for the heating means, said control means including means rendering the heating means inoperative in response either to the attainment of a predetermined temperature within the adsorber or an excessive pressure within said heat exchanger system and rendering the heating means effective only if the temperature of the evaporator is sufficiently high, the temperature of the adsorber is sufficiently low and the pressure in the heat exchanger system is sufficiently low, valve means controlling the flow of the heat exchange medium through the heat dissipating coil, and means responsive to the operation of 10 said heating means for causing the closure of said valve means.

9. In apparatus of the character described, in combination, means adapted to give off a refrigerant when heated and to take up said refrigerant when cooling, an evaporator connected in fluid flow relationship with said means, a heat source associated with said means, means controlling said heat source including an electric circuit having a switch means therein responsive to 15 the temperature of said first means and arranged to close at a relatively low temperature thereof and to open at a relatively high temperature thereof, valve means controlling the flow of the heat exchange medium through the heat dissipating coil, and means responsive to the operation of 20 said heating means for causing the closure of said valve means.

10. In apparatus of the character described, in combination, means adapted to give off a refrigerant when heated and to take up said refrigerant when cooling, an evaporator connected in fluid flow relationship with said means, a heat source associated with said means, means controlling said heat source including an electric circuit having a switch means therein responsive to 25 the temperature of said first means and arranged to close at a relatively low temperature thereof and to open at a relatively high temperature thereof, valve means controlling the flow of the heat exchange medium through the heat dissipating coil, and means responsive to the operation of 30 said heating means for causing the closure of said valve means.

11. In apparatus of the character described,

55 in combination, means adapted to give off a refrigerant when heated and to take up said refrigerant when cooling, an evaporator connected in fluid flow relationship with said means, a heat source associated with said means, means controlling said heat source including a valve, means responsive to the temperature of said means for abruptly closing said valve at a predetermined relatively high temperature thereof, means responsive to the temperature of the evaporator arranged to gradually open the valve as the 60 evaporator temperature rises, said means responsive to the temperature of the first means being arranged to permit opening of the valve if the temperature of the first means is below said 65 predetermined temperature.

12. In apparatus of the character described, in combination, means adapted to give off a refrigerant when heated and to take up said refrigerant when cooling, an evaporator connected in fluid flow relationship with said means, a heat

source associated with said first means, means controlling said heat source including a valve, means responsive to the temperature of said first means for abruptly closing said valve at a predetermined relatively high temperature thereof, means responsive to the temperature of the evaporator arranged to gradually open the valve as the evaporator temperature rises, said means responsive to the temperature of the first means being arranged to permit opening of the valve if the temperature of the first means is below said predetermined temperature, and additional means responsive to a condition which is a measure of the temperature of the heat source for closing said valve.

13. In an adsorption refrigeration system of the class described, an adsorber, a condenser and an evaporator operatively connected to-

gether, means for changing the temperature of said adsorber, means cooperating with the first mentioned means for causing the latter to cool the adsorber, and means responsive to a condition brought about by the need for reactivation of the adsorber for rendering the second mentioned means inoperative.

14. In an adsorption refrigeration system of the class described, an adsorber, a condenser and an evaporator operatively connected together, means for changing the temperature of said adsorber, means cooperating with the first mentioned means for causing the latter to cool the adsorber, and means responsive to the temperature of the adsorber for rendering the second mentioned means inoperative.

ALWIN B. NEWTON.
